SAFETY JOINT

Fred N. Osmun, Houston, Tex.

Application August 23, 1937, Serial No. 160,453

5 Claims. (Cl. 255—28)

This invention relates to a safety joint.

An object of the invention is to provide a safety joint specially adapted to be inserted into a drill stem used in rotary well drilling and by the use of which the stem may be readily parted for removal in case of necessity.

As is well known, the ordinary type of drill stem used in rotary well drilling is made up of a number of sections connected together by threads. This stem is used for driving the drill at the lower end thereof. Sometimes the drill becomes stuck in the bore and can not be withdrawn and in such event, it is desirable to unscrew, withdraw and save the drill stem. The safety joint herein described may be located in the stem adjacent the drill so that in case the drill becomes stuck the stem may be parted at the safety joint, and, as hereinafter described, withdrawn and thus recovered.

It is one of the principle objects of the invention to provide a safety joint of the character described which is not liable to become unscrewed during ordinary drilling operations but which may be readily unscrewed in case of necessity and when it is desired to separate the drill stem and withdraw it.

During drilling operations it often happens that the drill becomes temporarily stuck or held against rotation and in such case when the drill stem is placed under torsional strain, sufficient to release the drill, it causes the lower portion of the stem to spin, sometimes resulting in the accidental unscrewing of a conventional type of safety joint, if the same is used. With the improved type of safety joint herein described, this is not possible for the reason that the relatively rotatable parts of the joint are locked against unscrewing until it is desired to release the same to permit the separation of the stem.

It is a further object of the invention to provide a safety joint of the character described whose parts, or sections, are connected by a novel type of thread of such construction that it will take excessive torsional strain without the tendency to gall or "freeze."

Reference is here made to my co-pending application, Serial No. 292,279, filed December 15, 1939, for Safety joint covering certain features of the invention also disclosed but not claimed herein.

With the above and other objects in view, the invention has particular relation to certain novel features of construction, operation and arrangement of parts, examples of which are given in this

specification and illustrated in the accompanying drawing, wherein:

Figure 1 shows a side view, partly in section, of one form of the safety joint.

Figure 2 shows a cross sectional view thereof, 5 taken on the line A—A of Figure 1.

Figure 3 shows an enlarged fragmentary side view of the pin member.

Figure 4 shows a side view, partly in section, 10 of another embodiment, and

Figure 5 shows a cross sectional view taken on the line B—B of Figure 4.

Referring now more particularly to the drawing, wherein like numerals of reference designate the same parts in each of the figures, the 15 numeral 1 designates a driving member such as a drill stem used for rotary well drilling. As is well known, the drill stem is made up of sections connected by threads. It is driven from the rotary at the ground surface and drives the drill at- 20 tached to the lower end thereof. The type of safety joint shown in Figure 1 is preferably incorporated into the drill stem just above the drill, although it may be incorporated into the stem at any point. It embodies a box member 2, at- 25 tached to the lower end of the stem proper, and a pin member 3, whose lower end is threaded for connection to a drill collar or other coupling beneath. The pin member 3 is threaded into the box member 2. The interconnecting threads 30 embody spiralled scrolls 4, 5, the former in the box member 2 and the latter on the pin member 3.

The scroll like threads 5 fit nicely in the cor- 35 responding threads 4 when the parts are screwed together. The box and pin members 2 and 3 also have the opposing faces 6 and 7 which are pitched reversely with respect to the pitch of said threads and which abut when the pin is screwed home into the box and which, upon further relative 40 rotation of the pin and box, effect a relative end- wise movement of the connected parts, so as to distribute the torsional strain and to prevent the parts from becoming screwed too tightly together, thus eliminating any tendency of the 45 threads to "freeze" or gall.

The upper end of the pin member 3, may be tapered and formed with teeth as 8 and threaded into the upper end of the pin there is a tubular 50 nipple 9.

Within the box member 2 there is a tubular plunger 10 mounted on the upper end of which there is an upwardly opening cup ring 11 which forms a close fitting joint with the inner wall of the box member 2. The lower end of the plunger 55

10 fits over the nipple 9 and there may be an annular packing 12 countersunk into said plunger and fitted closely around said nipple. The lower end of the plunger is flared and formed with 5 teeth 13 arranged to intermesh with the teeth 8 as shown in Figure 1. The plunger 10 has external, vertical keys 14 which work in keyways 15 in the box member 2. These keyways 15 are cut in the inwardly thickened portion of the box 10 member 2, the upper end of said inwardly thickened portion forming an inside annular shoulder 16. The upper end of the plunger 10 has an external annular flange 17 and interposed between the shoulder 16 and flange 17 there is a coil spring 18 which normally holds the plunger 10 elevated and the teeth 13 out of mesh with the teeth 8. During ordinary drilling operations drilling fluid is forced under pressure down through the drill stem. The pressure of the drilling fluid holds the 20 plunger 10 in its lower position with the spring 18 compressed and with the teeth 13 engaged with the teeth 8. The box 2 and pin 3 are thus positively locked against unscrewing. Should the drill, or the portion of the drill stem beneath the 25 safety joint, become stuck, the pump for forcing the drilling fluid down through the drill stem may be stopped whereupon, the pressure being relieved, the spring 18 will immediately elevate the plunger 10 and release the teeth 13 from the teeth 8. The weight of the drill stem may then 30 be released, that is, the drill stem above the safety joint may be permitted to move downwardly and the sloping face 6, riding on the sloping face 7, will cause the box member 2 to turn to the left 35 slightly, thus breaking the joint. In other words, the column stress of the drill stem above the safety joint will cause the safety joint to partially unscrew or break. The drill stem may then be safely reversed, or turned to the left, and it will 40 part at the safety joint without danger of being separated at one of the joints connected by the ordinary threads. The operator is thus enabled to part the drill stem and recover the major portion thereof should the drill become so tightly 45 stuck that it can not be recovered. In the form shown in Figure 4 and Figure 5, the plunger 10a has an external annular shoulder 16a and a coil spring 18a surrounds the upper end of the plunger 10a and is interposed between the shoulder 16a and the lower end of the section of 50 the drill pipe above. This spring normally holds the teeth 13 of the plunger in mesh with the teeth 8 at the upper end of the pin 3. Beneath the shoulder 16a the box member 2a has the inside vertical keys 14a which are received by the external vertical keyways 15a in the plunger, whereby said parts are permitted to relatively 55 move longitudinally but are locked against relative rotation.

60 In this form the spring 18a will at all times maintain the teeth 13 in mesh with the teeth 8, thus locking the pin and box against unscrewing. Should the drill, or drill stem become stuck, a suitable grappling tool may be lowered down 65 through the drill stem and engaged with the plunger 10a and said plunger pulled upwardly to release the intermeshing teeth and thereupon, upon reverse rotation of the drill stem, the safety joint will be readily unscrewed as before and the

drill stem thus recovered. It is obvious that the type of safety joint shown in Figure 4 may be located at different points in the drill stem and if the drill stem is stuck in such manner that upon release of one of the lower safety joints the 5 stem can not be pulled, one of the safety joints above may be released and that portion of the drill stem above then backed off and recovered.

The drawing and description disclose what is now considered to be preferred forms of the invention by way of illustration only, while the broad principle of the invention will be defined by the appended claims.

What I claim is:

1. A safety joint comprising a box member, a pin member having a threaded connection with the box member, a slidably mounted locking device in the box member movable into one position to interlock with the pin member and into another position to release the pin member and a yieldable member for moving said locking device into released position.

2. A safety joint comprising a tubular box, a pin screwed into the box, a slidably mounted locking device in the box, said pin and locking device 25 having intermeshing teeth whereby they may be locked against relative rotation when the locking device is in active position and released when the locking device is in inactive position, means for preventing rotation of the locking device relative 30 to the box, yieldable means for moving the locking device into inactive position and means adapted to be actuated by fluid under pressure to move said locking means to active position.

3. A safety joint comprising a tubular box, a 35 tubular pin threaded into the box, a tubular plunger slidably mounted in the box and anchored against rotation relative to the box, said plunger and pin having teeth adapted to intermesh upon application of fluid under pressure 40 to the plunger and yieldable means normally maintaining said teeth out of mesh.

4. A safety joint comprising two tubular parts, one of said parts being formed with an internally threaded box and the other of said parts being 45 formed with an externally threaded pin adapted to be screwed into the box, a plunger having a slidable splined connection with the box, said plunger and pin having intermeshing parts adapted to intermesh, upon application of fluid 50 under pressure to the plunger, to lock the pin against rotation relative to the box and yieldable means normally holding said intermeshing parts in released position.

5. A safety joint comprising two tubular parts, 55 one of said parts being internally threaded and the other part an externally threaded pin adapted to be screwed into said internally threaded part, a tubular locking device having a splined connection with the internally threaded part, 60 said locking device and pin being shaped to intermesh to lock the pin against unscrewing, means subject to the pressure of an operating fluid and effective to actuate the locking device into said intermeshing relation with the pin and 65 means for releasing the locking device from the pin to permit operation of said parts.

FRED N. OSMUN.
